7 Claims. (Cl. 315—27)

1

The invention relates to a circuit-arrangement for producing a saw-tooth current in an inductance coil exhibiting both inductance and resistance with the aid of a pulse-like voltage this voltage having a constant value between the pulses and for a longer time period than the duration of each pulse. Circuit-arrangements of this kind are used, for example, for deflecting cathode-rays in cathode-ray tubes, the coil being used as a deflecting coil. In this case the pulse-like voltage may, for example, be obtained from the secondary of a transformer, the primary of which is included in the output circuit of a time-base generator, this generator being designed such that during the fly-back of the saw-tooth current of the generator a voltage of constant value is set up across the primary, and thus also across the secondary, of the transformer.

In view of the use of such circuit-arrangements, it is generally desirable that the saw-tooth current produced in the coil should vary linearly with time during the fly-back. However, owing to the presence of the resistance in the coil, this will not be the case. If, for example, a direct current voltage having a magnitude E is abruptly applied to such a coil, the coil has set up in it a current

$$i = \frac{E}{r} \left(1 - e^{-\frac{rt}{L}} \right)$$

t =time, L =inductance of the coil, r =resistance of the coil. As revealed by progression development, the deviation from straight line relationship is, in this case, proportional to the exponent

$$\frac{rt}{L}$$

The aforesaid pulse-like voltage has the effect of setting up in the coil, during the fly-back, currents deviating from a straight-line relationship proportional to

$$\frac{r}{L}$$

and to the time duration of the period of saw-tooth current.

The time duration of the period is generally prescribed, and

$$\frac{r}{L}$$

cannot be made arbitrarily small, since this entails higher cost, and a given size is necessary for use in view of available space and permissible dimensions.

5 The object of the invention is to provide a circuit-arrangement, in which the deviation from linearity of the saw-tooth current is considerably smaller than in the well-known circuit-arrangements. The invention is based on recognition of the fact that this deviation is primarily due to phase distortion for the various frequencies of the components into which the voltage applied in a pulse-like fashion can be broken down.

10 15 If the voltage applied is decomposed into sinusoidal components, the current i passing through the coil would be ideally equal to

$$\frac{E}{j\omega L}$$

20 where $\omega = 2\pi f$ and f is the frequency, E designating the voltage applied. However, owing to the presence of the resistance, r ,

$$25 i = \frac{E}{r+j\omega L} = \frac{E}{j\omega L} \times \frac{j\omega L}{r+j\omega L}$$

is produced, in which the second factor causes the deviations. If this factor were a constant for all frequencies, the ideal case, that is to say a linearly varying saw-tooth current, would be 30 achieved. Now, the tangent of the phase angle of this factor, which is most essential for the deviation from linearity, is practically equal to zero for high frequencies. For low frequencies, for example the fundamental frequency of the 35 saw-tooth current, the tangent has a comparatively large value. If, for example, use is made of a coil having

$$40 \frac{r}{L} = 1000, \tan \varphi = \frac{r}{\omega L} \text{ is equal to } \frac{1}{60}$$

45 where $\omega = 6.10^{-4}$ radians/sec, and where L is in henries and r is in ohms.

The circuit-arrangement according to the invention permits of reducing this value for $\tan \varphi$ 45 at low frequencies to a materially smaller value, so that a greatly improved approximation of the linear form of the saw-tooth current is obtained.

In order that the invention may be more clearly understood and readily carried into effect, it 50 will now be explained more fully with reference to the accompanying drawing, in which Figs. 1

and 2 illustrate a circuit-arrangement of the said kind and the pulse-like voltage supplied thereto respectively. Figure 3 is a modification of Figure 1. The circuit-arrangement shown in Fig. 1 comprises the series combination of a coil 1 comprising inductance designated L_1 and resistance designated r_1 , and a parallel circuit, of which one branch includes a coil 2 comprising inductance designated L_2 and resistance designated r_2 , and the other branch a coil 3 comprising inductance designated L and resistance designated r . A pulse-like voltage having the shape illustrated in Fig. 2 is supplied to the input terminals 4, 5. This voltage is constituted by periodical pulses a, b, c having a width equal to t_1 , between which a constant voltage is set up for a time equal to t_0 which exceeds t_1 . A voltage of this kind can be produced in a number of ways which are not of interest to the present invention.

If this voltage is assumed to be composed of sinusoidal components and if in the circuit-arrangement shown in Fig. 1 currents i_1, i_2 and i flow in coils 1, 2 and 3 respectively, the following relations apply for each value of ω :

$$\begin{aligned} E &= i_1(r_1 + j\omega L_1) + i(r + j\omega L) \\ i(r + j\omega L) &= i_2(r_2 + j\omega L_2) \\ i_1 &= i_2 + i \end{aligned}$$

It follows, after some reduction:

$$i = \frac{E}{j\omega L} \times \left[\frac{j\omega r_2 L - \omega^2 LL_2}{rr_1 + rr_2 + r_1 r_2 + j\omega(r_2 L + r_1 L_2 + r_2 L_1 + r_1 L_2 + r_1 L) - \omega^2(LL_1 + LL_2 + L_1 L_2)} \right]$$

solving for the tangent of the phase angle, φ , of the factor between brackets which introduces the undesired distortion,

$$\tan \varphi = \frac{r_1 r_2^2 + rr_2^2 + rr_1 r_2 + \omega^2(r_1 L_2^2 + r_1 LL_2 + r_1 L_2 + r_2 L_2^2 - r_2 L_1 L)}{\omega(r_1 r_2 L + r_2^2 L_1 + r_2^2 L + rr_1 L_1 - rr_1 L_2) + \omega^3(LL_1 L_2 + L_1 L_2^2 + LL_2^2)}$$

As above derived, if the pulse-like voltage is directly applied to the coil L , r , a tangent of the phase-angle equal to

$$\frac{r}{\omega L} = \tan \varphi_1$$

is found. Thus, in order to reduce phase distortion, $\tan \varphi$ must always be smaller than $\tan \varphi_1$.

A further explanation of the value found for $\tan \varphi$ indicates that $\tan \varphi$ will, in actual fact, always be smaller than $\tan \varphi_1$, if the conditions are satisfied that

$$\frac{r_2}{L_2} \text{ is larger than } \frac{r}{L}$$

and, also

$$\frac{r_1}{L_1} \text{ is smaller than } \frac{r}{L} + \frac{r_2}{2L_2}$$

The first condition indicates that the quality of coil 2 composed of L_2 and r_2 which is connected in parallel with the coil 3 composed of L and r must have a lower figure of merit than the latter.

According to a further embodiment of the circuit-arrangement the coil 1, composed of L_1, r_1 is such that

$$\frac{r_1}{L_1} \text{ is smaller than } \frac{r}{L}$$

so that the figure of merit of the series-connected coil is higher than that of the coil L, r .

This ensures a further reduction of the value of $\tan \varphi$.

The optimum effect of the circuit-arrangement is obtained if, according to a further embodiment of the circuit-arrangement according to the invention, provision is also for the coils 1 and 2 to be such that the condition:

$$\frac{r_2}{L_2} = \frac{r_1}{L_1} \left(1 + \frac{L_2}{L} \right) + \frac{r}{L} \left(1 + \frac{L_2}{L_1} \right)$$

is fulfilled.

If this condition is fulfilled, a minimum value is found for $\tan \varphi$ at lower values of ω . On considering the expression found above for $\tan \varphi$, which can be written in the form of

$$\tan \varphi = \frac{a + b\omega^2}{c\omega + \alpha\omega^3}$$

in which a, b, c and d are simplified functions of the inductances and resistances, it is found for high values of ω to approach zero, owing to the presence of the term comprising ω^3 in the denominator of the fraction. At smaller ω , the term comprising ω^2 in the numerator is very important. The coefficient b is now equal to:

$$r_1 L_2^2 + r_1 LL_2 + r L_1 L_2 + r L_2^2 - r_2 L_1 L$$

If this coefficient is assumed to be zero, the above indicated condition is found.

Assuming $L_1 = \frac{1}{2} L_2 = 2L$ and $r_1 = \frac{1}{2}r$, from

$$\frac{r}{L} = 1000$$

45 a value of

$$\frac{1}{3840}$$

50 is found for an angular velocity of ω of 6.10^4 radius per second, that is to say approximately 64 times smaller than in the case of direct supply of this voltage to the coil. The values of r and L may be in ohms and henries. This results in a considerably improved approximation of the straight-line relationship of the sawtooth current.

According to a further, favourable embodiment of the circuit-arrangement according to the invention in Fig. 3, a capacity C_2 is included in the parallel branch in series with an auxiliary coil 2. This capacity may be expressed in farads. A further improvement in the shape of the sawtooth current can thus be ensured said improvement being a maximum if

$$C_2 = \frac{LL_1}{L_2(rr_1 + rr_2 + r_1 r_2)}$$

70 Those parts of the circuit-arrangement which correspond to parts of the circuit-arrangement shown in Fig. 1 are designated by like reference numerals.

For this circuit-arrangement also, a calculation similar to the preceding permits calculat-

ing the current i passing through the coil 3 for a given value of ω it being again found that

$$i = \frac{E}{j\omega L}$$

times a factor which introduces the distortion. It is found that the tangent of the phase-angle of this factor can be reduced again, if the previously derived conditions are fulfilled. The presence of the capacity permits, however, of also making sure that the absolute value of the factor itself varies only to a small extent throughout the entire frequency range. The optimum condition is ensured if the capacity C_2 is adjusted to the above-indicated value.

An illustrative example of values for the circuit shown in Fig. 3 may be given as follows:

$$\begin{aligned} L &= 3 \times 10^{-3} \text{ henries} \\ L_1 &= 3 \times 10^{-4} \text{ henries} \\ L_2 &= 3 \times 10^{-2} \text{ henries} \\ r &= 3 \text{ ohms} \\ r_1 &= 0.31 \text{ ohm} \\ r_2 &= 3360 \text{ ohms} \\ C_2 &= 2280 \mu\mu \text{ farads} \end{aligned}$$

What we claim is:

1. A circuit-arrangement for producing a sawtooth current in an inductance coil exhibiting an inductance L and a resistance r , including a pulse-like voltage which exhibits a constant value between the pulses and for a longer time than the duration of each pulse, wherein this pulse-like voltage is fed to a circuit, said circuit comprising the series combination of an auxiliary coil exhibiting an inductance L_1 and a resistance r_1 and a parallel circuit, of which one branch includes the inductance coil (L, r) and the other branch an auxiliary coil exhibiting an inductance L_2 and a resistance r_2 , and these auxiliary coils being of such value that

$$\frac{r_2}{L_2} \text{ is greater than } \frac{r}{L}$$

and

$$\frac{r_1}{L_1} \text{ is smaller than } \frac{r}{L} + \frac{r_2}{2L_2}$$

where r, r_1 and r_2 represent resistance in ohms and L, L_1 and L_2 represent inductance in henries.

2. A circuit-arrangement as claimed in claim 1, wherein the auxiliary coil (L_1, r_1) is of such value that

$$\frac{r_1}{L_1} \text{ is smaller than } \frac{r}{L}$$

3. A circuit arrangement to produce sawtooth electric variations in an inductance coil having an inductance designated L and a resistance component r comprising, a source of alternating current having a stepped wave shape, a first auxiliary coil having an inductance L_1 and a resistance component r_1 , a second auxiliary coil having an inductance L_2 and a resistance component r_2 , said second auxiliary coil coupled in parallel with the inductance coil, said source of desired signals supplied to a series connection of the said first auxiliary coil and the parallel coupling of the inductance coil and the said second auxiliary coil, and said first and second auxiliary coils having values with respect to the said inductance coil at which

$$\frac{r_2}{L_2} > \frac{r}{L}$$

and

$$\frac{r_1}{L_1} < \frac{r}{L} + \frac{r_2}{2L_2}$$

where

r, r_1 and r_2 =resistance in ohms
 L, L_1 and L_2 =inductance in henries

4. A circuit arrangement to produce sawtooth electric variations in an inductance coil having an inductance designated L and a resistance component r comprising, a source of alternating current having a stepped wave shape, a first auxiliary coil having an inductance L_1 and a resistance component r_1 , a second auxiliary coil having an inductance L_2 and a resistance component r_2 , said second auxiliary coil coupled in parallel with the inductance coil, said source of desired signals supplied to a series connection of the said first auxiliary coil and the parallel coupling of the inductance coil and the said second auxiliary coil, and said first and second auxiliary coils having values with respect to the said inductance coil at which

$$\frac{r_2}{L_2} > \frac{r}{L}$$

and

$$\frac{r_1}{L_1} < \frac{r}{L}$$

where

r, r_1 and r_2 =resistance in ohms
 L, L_1 and L_2 =inductance in henries

5. A circuit arrangement to produce sawtooth electric variations in an inductance coil having an inductance designated L and a resistance component r comprising, a source of alternating current having a stepped wave shape, a first auxiliary coil having an inductance L_1 and a resistance component r_1 , a second auxiliary coil having an inductance L_2 and a resistance component r_2 , said second auxiliary coil coupled in parallel with the inductance coil, said source of desired signals supplied to a series connection of the said first auxiliary coil and the parallel coupling of the inductance coil and the said second auxiliary coil, and said first and second auxiliary coils having values with respect to the said inductance coil at which

$$\frac{r_2}{L_2} > \frac{r}{L}$$

$$\frac{r_1}{L_1} < \frac{r}{L} + \frac{r_2}{2L_2}$$

and

$$\frac{r_2}{L_2} = \frac{r_1}{L_1} \left(1 + \frac{L_2}{L_1} \right) + \frac{r}{L} \left(1 + \frac{L_2}{L_1} \right)$$

where

r, r_1 and r_2 =resistance in ohms
 L, L_1 and L_2 =inductance in henries

6. A circuit arrangement to produce sawtooth electric variations in an inductance coil having an inductance designated L and a resistance component r comprising, a source of alternating current having a stepped wave shape, a first auxiliary coil having an inductance L_1 and a resistance component r_1 , a second auxiliary coil having an inductance L_2 and a resistance component r_2 , a capacitive element in series with the said second auxiliary coil, said second auxiliary coil and capacitive element coupled in parallel with the

inductance coil, said source of desired signals supplied to a series connection of the said first auxiliary coil and the parallel coupling of the inductance coil and the said second auxiliary coil and capacitive element, and said first and second auxiliary coils having values with respect to the said inductance coil at which

$$\frac{r_2}{L_2} > \frac{r}{L}$$

and

$$\frac{r_1}{L_1} < \frac{r}{L} + \frac{r_2}{2L_2}$$

where

r , r_1 and r_2 =resistance in ohms
 L , L_1 and L_2 =inductance in henries

7. A circuit arrangement to produce sawtooth electric variations in an inductance coil having an inductance designated L and a resistance component r comprising, a source of alternating current having a stepped wave shape, a first auxiliary coil having an inductance L_1 and a resistance component r_1 , a second auxiliary coil having an inductance L_2 and a resistance component r_2 , a capacitive element in series with the said second auxiliary coil, said second auxiliary coil

and capacitive element coupled in parallel with the inductance coil, said source of desired signals supplied to a series connection of the said first auxiliary coil and the parallel coupling of the inductance coil and the said second auxiliary coil, and said first and second auxiliary coils and capacitive element having values with respect to the said inductance coil at which

$$\frac{r_2}{L_2} > \frac{r}{L}$$

$$\frac{r_1}{L_1} < \frac{r}{L} + \frac{r_2}{2L_2}$$

and

$$C_2 = \frac{L_1 L}{L_2 (r_1 r_2 + r r_2 + r r_1)}$$

where

r , r_1 and r_2 =resistance in ohms
 L , L_1 and L_2 =inductance in henries, and
 C_2 =capacity in farads
